UNITED STATES PATENT OFFICE.

PAUL OTTO ELTERICH, OF CHICAGO, ILLINOIS, ASSIGNOR TO ELEONORE M. VON VAREL, OF NEW YORK, N. Y.

RIFLED BULLET-SHELL FOR SHOTGUNS.

SPECIFICATION forming part of Letters Patent No. 672,824, dated April 23, 1901.

Application filed November 19, 1900. Serial No. 37,007. (No model.)

To all whom it may concern:

Be it known that I, PAUL OTTO ELTERICH, a citizen of the United States of America, and a resident of Chicago, in the county of Cook and State of Illinois, have invented certain new and useful Improvements in Rifled Bullet-Shells for Shotguns, of which the following is a specification.

The main object of my invention is to provide a shell suitable to be fed to the barrel from the magazine of a repeating shotgun and containing a rifled barrel adapted to receive and discharge a bullet-cartridge.

The particular objects of the different parts with which I put my invention into practice will be understood from the following description with reference to the accompanying drawings, in which—

Figure 1 is a partly-sectional view of a Winchester repeating shotgun, showing one of my shells in the magazine and another of said shells on the carrier in proper position to be conveyed to the barrel of the gun. Fig. 2 is a plan of one of my improved shells. Fig. 3 is a longitudinal central section of same. Fig. 4 is an enlarged section on the line 4-4 of Fig. 3. Fig. 5 is an enlarged end view of said shell.

The shell shown has the outer casing 1, having slots 2 therein and having the parts between the slots bulging slightly, as at 3 in Figs. 1 and 2. A barrel 5 is rigidly secured in the casing 1 by means of the bushings 6 and 7 and is provided with the interior rifling 8. The base of the barrel has a recess 9 therein for receiving the bullet-cartridge 10. The barrel 5 is made flush with the casing 1 at each end, so as to provide an exterior form similar to that of the standard shotgun-shells. The rifling will be made of lower pitch or quicker twist than that in the ordinary rifle-barrel.

The operation of the device is as follows: The shells are placed in the magazine 11 of the shotgun in the usual manner. When the slide-handle 12 is drawn back, one of the shells is moved upon the carrier 13, as shown in Fig. 1. When the slide-handle is again moved forward, this shell is carried to the barrel 14 and forced into said barrel by means of the breech-lock 15 in the usual manner. It is plain that these shells may be used as often as desired, it being necessary merely to reload the same with a new bullet-cartridge.

It will be understood that my improved shells may be used in other breech-loading shotguns which are not of the repeating-gun type; but said shells are particularly designed for use in a repeating shotgun.

I make no claim to the construction of the shotgun shown, since the same is of a well-known type and is shown merely to illustrate the use of my shells.

It will be understood that some of the minor details of construction in the shell shown may be altered without departing from the spirit of my invention. I therefore do not confine myself to such details except as hereinafter limited in the claims.

What I claim as my invention, and desire to secure by Letters Patent, is—

1. A shell for shotguns, having rigidly secured therein a rifled barrel, adapted to receive and discharge a bullet-cartridge, substantially as specified. 75

2. A shell for shotguns, having rigidly secured therein a rifled barrel, adapted to receive and discharge a bullet-cartridge, said parts being of suitable form to permit the use of said shell in series with others in a magazine-shotgun, substantially as specified. 80

3. A shell for shotguns having rigidly secured therein a rifled barrel adapted to receive and discharge a bullet-cartridge, said shell having an outer resilient part adapted 85 to bear against the inner walls of a shotgun-barrel, and said parts being of suitable construction to permit the use of said shell in series with others in a magazine-shotgun, substantially as specified. 90

4. A shell for shotguns comprising the outer slotted casing having the resilient bulging part between the slots, and the rifled barrel rigidly secured in said casing, for the purpose specified. 95

5. A shell for shotguns comprising the outer slotted casing having the resilient bulging parts between the slots, and a barrel rigidly secured in said casing, for the purpose specified. 100

Signed at Chicago, Illinois, this 17th day of November, 1900.

PAUL OTTO ELTERICH.
